(57) **CLAIM**

The ornamental design for a customer engagement kit, as shown and described.

DESCRIPTION

FIG. 1 is a front perspective view of a customer engagement kit, showing my new design;

FIG. 2 is a front elevation view thereof;

FIG. 3 is a rear elevation view thereof;

FIG. 4 is a left-side elevation view thereof; the right-side elevation view being a mirror image thereof;

FIG. 5 is a top plan view thereof, the bottom plan view being a mirror image thereof; and,

FIG. 6 is a front perspective view of the customer engagement kit shown in a used condition.

The evenly spaced broken lines showing components for supporting the spinning wheel portion of the customer engagement kit in FIG. 6 depict environmental subject matter and form no part of the claimed design.

The remaining evenly spaced broken lines shown in the drawings depict portions of the customer engagement kit that form no part of the claimed design.

The dash-dot-dash broken lines shown in the drawings denote a boundary of the claim and form no part thereof.
